(57) **CLAIM**

The ornamental design for an electrical docking device, as shown and described.

DESCRIPTION

FIG. 1 is a right view of an electrical docking device according to my design;

FIG. 2 is a left view thereof;

FIG. 3 is a top view thereof;

FIG. 4 is a bottom view thereof;

FIG. 5 is a rear view thereof;

FIG. 6 is a front view thereof; and,

FIG. 7 is a right, front, top perspective view thereof.

The broken lines in the drawings show portions of the electrical docking device which form no part of the claimed design.
